UNITED STATES PATENT OFFICE.

WILLIAM E. HARPER, OF CHICAGO, ILLINOIS.

DENTAL INSTRUMENT.

SPECIFICATION forming part of Letters Patent No. 651,922, dated June 19, 1900.

Application filed December 18, 1899. Serial No. 740,751. (No model.)

To all whom it may concern:

Be it known that I, WILLIAM E. HARPER, a citizen of the United States, residing at No. 3441 Wabash avenue, Chicago, in the county 5 of Cook and State of Illinois, have invented certain new and useful Improvements in Dental Instruments, of which the following is a specification.

This invention relates to improvements in 10 that class of dental instruments in which a rotary tool, technically called a "bur," is detachably secured in an angular head in which is appropriately journaled a shaft or shafts by means of which rotary motion is im- 15 parted to the tool from a flexible shaft in any suitable manner, the angular head being screw-threaded or otherwise attached to a handpiece or handle by which the instrument is manipulated. Numerous examples 20 of dental instruments of this general class are found in the prior art, in many of which the angle of the axis of the tool may be ad- justed and set with relation to the axis of the handle for facilitating operation upon differ- 25 ent kinds, locations, and parts of tooth-cavities; but the particular kind of head to which my invention is more particularly applicable is the right-angled head with adjustability, such heads being now commonly sold upon 30 the market. Such heads generally consist of a right-angled casing, like the elbow of a stovepipe, the driving-shaft being journaled in one branch of the casing and the rotary tool being appropriately journaled in the 35 other section, with suitable beveled gears connecting the two shafts. Such heads are now generally screwed into a straight handle, through which extends a shaft communicat- 40 ing power from a flexible shaft to the tool- driving shaft. The objection to all of such instruments, whether of the fixed right-angular type or of the adjustable angular type, is that while the axes of the handle and tool are in the same vertical plane they are in 45 widely-different horizontal planes and are therefore very unstable, and especially in applying pressure to the rotary cutting - tool through the handle either axially or laterally, there being constant liability of the instru- 50 ment canting, wabbling, or rocking about upon the bur as a pivot, and as the bur must necessarily rotate at a high speed the

danger incident to operating adjacent to a thin wall or upon side walls and the difficulty of holding the tool properly to its work as 55 against wabbling and jumping from point to point in the cavity will be readily appreciated.

The primary object of my invention is to avoid all of these difficulties by having the 60 pressure applied to the cutting-tool or bur in a plane substantially coincident with the cutting edge of the bur.

Another object is to have the axis of the handle oblique to the axis of the cutting-tool 65 and so disposed as to intersect the axis of the cutting-tool substantially at the cutting edge or point thereof, whereby all tendency to instability, lateral canting, or wabbling of the tool is avoided.

A further object is to have the handle of 70 simple and novel construction, combining strength and rigidity in the maximum degree, and yet so constructed as to afford proper bearings for the angular transmission of 75 power therethrough, to afford ready access to the transmitting-gears both in assembling and separating the parts, and so as to afford a cheap construction permitting the proper boring and dressing of the angularly-dis- 80 posed bearings and faces for the gearing while the tool is straight and prior to its being bent to the angular form necessary to bring its axis to a line that will intersect the axis of the cutting-tool substantially at the 85 cutting edge or point of the tool.

These and such other objects as may hereinafter appear are attained by the devices illustrated in the accompanying drawings.

Figure 1 is a side elevation, partly broken 90 away, of a dental instrument embodying my invention. Fig. 2 is a diagrammatic elevation thereof. Fig. 3 is an inverted plan view of the same, and Fig. 4 is a perspective view of the cap covering the gear-chamber in the 95 handle.

Similar letters of reference indicate the same parts in the several figures of the drawings.

Referring by letter to the accompanying 100 drawings, A indicates a right-angular head of any construction, into one end of which, as at B, is screwed or otherwise secured the handle C, and in the other end of which is

suitably journaled the cutting-tool D, which, as usual, is detachable from the head for interchangeability from other tools having differently-shaped cutting points or edges, the cutting-tool being usually connected by a bevelled gear with a short shaft (not shown) journaled in the other section of the head, which is in turn detachably coupled to the tool-driving-shaft E. I have not deemed it necessary to illustrate or describe in detail the construction of this head, because it is identical with those now generally found upon the market and is well understood by those skilled in the art, and so far as relates to the broad idea of my invention the exact shape and construction of this head is immaterial so long as it has a cutting-tool and a shaft at angles to each other and is adapted to meet the requirements imposed by my handle, as will now be described.

The handle C is angular, as clearly shown in Figs. 1 and 2, the main body portion thereof, F, which is held in the hand, being disposed at an angle to the end G thereof, to which the head A is secured, preferably by a screw. The angle between the parts F and G of the handle is intended to be such that the axis of the handle (represented by the dotted lines H H in Fig. 2) is oblique to the axis of the cutting-tool or bur D and is so disposed with relation thereto as to intersect the axis of said tool substantially at the cutting edge or point thereof. When so disposed, the plane of pressure applied to the handle is substantially coincident with the plane of the cutting edge or point of the tool, and hence when pressure is applied in a direction substantially parallel with the axis of the cutting-tool there will be no tendency whatever to instability, wobbling, or canting of the tool, and this tendency is reduced to the minimum when pressure is applied laterally of the tool—as, for instance, in working on the side wall of a cavity—for the point of resistance will be coincident with the plane of pressure. This general feature of construction is of the utmost importance, because it enables the manipulation of the instrument with great delicacy and accuracy, as well as with great power, notwithstanding the high speed at which the cutting-tool is rotating and regardless of whether the work is being done upon a surface at right angles to or substantially parallel with the axis of the cutting-tool, for with the liability to cant and wobble when pressure is applied the operator need trust to himself only to the proper placing of the tool, while being free to apply such pressure as may be needed in such direction as it may be needed. This would not be true were the axis of the handle at right angles to the axis of the cutting-tool or at any other angle thereto without intersecting the axis of the cutting-tool substantially at the point or cutting edge thereof. This advantage is of especial importance in operating against or adjacent to very thin walls, where

a slight motion, unexpected or uncontrollable, of a very small fraction of an inch would break down the wall and cause excruciating pain and possibly serious and lasting consequences to the patient. The construction of the handle is also novel and greatly reduces the cost of the instrument in that instead of having the handle cast in the shape shown in the drawings I propose to have it formed in the first instance of a straight tubular blank, so that a single tool can be used for drilling the bearings for the tool-driving shaft E as well as the seat for the bushing I of the handle-shaft J and at the same time provide ready access to the gear-cavity K for dressing the face thereof opposing the backs of the gears. This handle is formed straight in the first instance with the solid central portion from which is formed by milling the two diaphragms L and M, affording bearings for the shafts E and J, said diaphragms being suitably distanced apart. While the blank is still straight, the wall thereof at one side is milled out, as shown more clearly in Fig. 3, substantially half of the circumference thereof between the diaphragms, which so weakens the casing at this point that it may be bent to the form shown without disturbing the proper alignment of the bearings in the diaphragms L and M for the shafts E and J. The space between the diaphragms constitutes the gear-chamber K, and the opening formed by milling out the side thereof affords a ready means of access to the chamber to facilitate the securing of the angularly-disposed gears N and O upon the shafts E and J, respectively. The opening caused by milling away the wall of the gear-cavity, as before explained, is closed by a cap P, (shown in detail in Fig. 4,) which cap is secured in place by screws and is so shaped as to give a smooth finish to the handle. Obviously if the handle were cast in the shape shown it would involve considerably more expense to drill the bearings for the shafts E and J, which would have to be done upon two different angles and in two different operations, besides which considerable difficulty would be encountered in such angular drilling in having the proper intersection between the axis of the shaft so that the gears would work smoothly and freely, and such difficulties I have found by experience would so increase the cost of the handle as to make it commercially impracticable.

While the milling out of the side of the handle weakens it, in comparison with the end portions of the handle, to such an extent as to insure the proper bending taking place at the proper point in the handle, still such cut-out portion does not affect the rigidity of the handle in operation, for ample stock is left to insure that the bent handle will resist any pressure to which it may ever be subjected in use.

While I prefer the angular handle of the general form and construction herein shown

and described, I do not desire to limit myself to the same, for so far as relates to the broad idea of my invention the shape and construction of the handle, as well as of the tool-carrying head, is immaterial so long as the axis of the handpiece of the handle, to which pressure is primarily applied, is oblique to the axis of the tool and intersects the same substantially at the cutting edge or point thereof, for it is within the contemplation of my invention that the sections F and G of the handle may be separable from one another and the section G, comprising the angular portion of the handle, may be formed with or attached to the head, leaving the handle proper or the handpiece straight. The fixed right-angled head illustrated in the drawings in conjunction with the angular handle produces an exceptionally handy instrument, which is simple, cheap, and compact and not liable to get out of order; but it is obvious that a multangular head may be used either with the angular handle shown or with a straight handle so disposed that the axis thereof shall have the same relation to the axis of the cutting-tool as that shown in the instrument herein illustrated and described.

Having thus fully described my invention, what I claim, and desire to secure by Letters Patent, is—

1. In a dental instrument, the combination with a head and a rotary cutting-tool mounted therein, of a handpiece therefor said head and cutting-tool being disposed in a plane at an angle to the axis of the handpiece and a rotary shaft in said handpiece operatively connected with said tool, the axis of said

handpiece being so disposed as to intersect the axis of the cutting-tool substantially at the cutting edge or point thereof, substantially as described.

2. In a dental instrument, the combination with an angular head and a rotary cutting-tool mounted therein, of an angular handle and a shaft journaled therein and operatively connected with the cutting-tool, the axis of the handpiece of said handle being disposed oblique to the axis of the cutting-tool so as to intersect the same substantially at the cutting edge or point of the tool, substantially as described.

3. In a dental instrument, the combination with an angular head and a rotary cutting-tool mounted therein, of an angular handle having a gear-chamber substantially at the juncture of its angular portions, bearings at either side of said chamber, shafts journaled in said bearings and gears connecting said shafts, one of said shafts being operatively connected with the rotary cutting-tool and the other of said shafts constituting a driving-shaft, substantially as described.

4. As a new article of manufacture, a handle for dental instruments comprising an angular metallic tube cut away at the bend thereof and provided with a gear-chamber, a removable cap for said chamber, bearings on opposite sides of said chamber, shafts journaled in said bearings and gears connecting said shafts, substantially as described.

WILLIAM E. HARPER.
